UNITED STATES PATENT OFFICE.

CELESTINO USUELLI, OF MILAN, ITALY.

CONSTRUCTION OF SEMIRIGID AIRSHIPS.

Application filed January 14, 1921. Serial No. 437,177.

To all whom it may concern:

Be it known that I, CELESTINO USUELLI, a subject of the King of Italy, and resident at Milan, in the Kingdom of Italy, have invented certain new and useful Improvements 5 in the Construction of Semirigid Airships, of which the following is a specification.

This invention relates to improvements in the construction of so-called semi-rigid airships, that is to say to air ships the gas bag of which consists of a cloth envelope stiffened by a metal girder running along its lower part and to which girder are hung or fastened the cars, the motors and propellers 15 of the driving plant and the stabilizing and steering surfaces, which constitute the concentrated loads.

The invention concerns more especially the shape of the stiffening girder and its 20 arrangement, as well as the attachment of the loads with a view to lessen the parts projecting out of the envelope, which is obtained by suppressing the conventional suspended cars, while providing, however, at 25 the same time, ample and commodious room for the crew and passengers.

This form of construction is particularly suited for airships of large dimensions.

It is schematically shown in the annexed 30 drawing in which:

Fig. 1 shows, in a side view, the complete airship;

Figs. 2 and 3 are respectively cross sections of same on lines XX and YY of Fig. 1;

Fig. 4 shows, on a larger scale, the lower 35 part of the section shown at Fig. 2;

Fig. 5 is a sectional view of the girder with a two-part covering applied thereon;

Fig. 6 is a side view of the covering along 40 its junction with the lower edge of the envelope;

Fig. 7 shows the manner of fastening together the adjoining cover flaps;

Fig. 8 shows the connection of the girder, 45 at its upper edges, with the envelope;

Fig. 9 is a sectional view of the girder with a one-piece covering applied thereon;

Fig. 10 is a schematical view of the rudder frame connected to the girder, and

Fig. 11 is a perspective view, on a larger scale, of the rudder frame connected to the girder with the girder covering omitted.

As it is shown in the drawing, the stiffening girder runs along the whole length of 55 the lower part of the envelope —b— and reaches the farthest end of the bow at the

height of the longitudinal axis of the envelope itself. The girder is of triangular cross section with its vertex downwards and comprises a series of triangular frames *a* 60 formed of a trellis work of steel or hard aluminium alloy pipes or of any other convenient metal, fastened together by means of other detachably mounted smaller beams *g* connecting the corresponding vertex of two successive triangles. The panels which result from this structure are rendered stiff and indeformable by means of diagonal pieces *j* preferably consisting of metal cables or wires. The girder thus formed is placed 70 with its upper horizontal face against the lower part of the envelope, which is preferably subdivided by cloth partitions into a convenient number of compartments in the usual manner.

The girder is covered externally with a strong covering depending from the envelope along the lines *z*—*z* where the envelope joins with the upper edges of the girder. The covering may consist of two halves 75 —*k'*— and —*k''*—, as shown in Fig. 5, or may be in a single piece —*k*—, as shown in Fig. 9. In either case a fastening —*r*— of well known type connects the adjoining edges. The cover, or its halves, are preferably composed of several sections, the adjoining edges of which are interconnected by lacings or seams —*s*—, as shown in Figs. 6 and 7. The lower edges of the envelope are connected to eyelets —*u*— provided in the 80 triangular frame —*a*— in the manner shown in detail in Fig. 8.

The bow is rendered indeformable by means of an umbrella like cage —*g*— made of metallic light frames —*p*— connected 95 with a certain number of circular light frames —*q*—.

Said cage is covered with a perfectly tightened cloth coated with Emaillite or the like varnish so as to form a true and regular 100 cap.

Also the envelope —*b*— carries in special sheaths set externally on the fore part of it, a number of ribs —*t*— which, when the envelope is filled with its fore part fitted with in the cage —*g*—, run for a certain length beyond the last frame —*q*— of the cage. The fastening of the envelope with the cage 105 is made along the lengths of the ribs —*t*— which are in connection with those at —*p*—.

A frame —*d*— supporting the direction and height rudders —*v*— and —*w*— re-

spectively, as shown in Fig. 11 is fastened at the rear end of the beam —*a*— below the bag —*b*—.

Horizontal and vertical fins —*v*—, —*u*— 5 acting as stabilizing surfaces are also provided in the usual way. Said fins may be, if desired made to carry the height and the direction rudder in the manner already known in other types of airships and thus 10 the frame —*d*— may be omitted.

The motors —*m*— are arranged overhanging in couples. In the drawing three couples are shown. They are placed on the two sides of the girder supported by a framing formed with light beams —*n*— and 15 rods —*i*— attached to the girder.

Each motor drives a screw —*o*— to which it is connected either directly or through a coaxial reduction gear. The radiators are 20 placed before the motors.

Along a good length of the girder, at a suitable height inside same is fitted a partition —*f*— which acts as a floor in the room reserved for the passengers and the 25 crew, within which are placed seats, tables, couches and all that is required for a long journey.

In connection with the framing supporting the motors are arranged the gangways 30 —*h*— which allow of reaching the driving plants for their management and supervision.

The eventual shocks in landing are attenuated by means of pneumatic buffers —*l*— 35 made of tight air filled bags.

The airship being supplied with more couples of independent motors, it may use only one couple and keep the others as a reserve, or it may use more couples at a 40 time according to the circumstances of navigation.

Claims:

1. In a semirigid airship, in combination with a gas bag, an external tubular metal 45 girder structure extending underneath said bag in close relation thereto, longitudinal cover flaps depending from said bag and enclosing said girder, and a stiffening cage at the bow end of said girder, said cage comprising curved radially directed ribs and a 50 plurality of annular frame members of re-

spectively decreasing diameter interconnecting said ribs.

2. In a semirigid airship, in combination with a gas bag, an external tubular metal 55 girder structure of substantially triangular cross-section extending underneath said bag in close contact therewith, side covers depending from said bag and enclosing said girder, a stiffening cage supported by the 60 front end of said girder, and a plurality of pairs of frames supported by said girder in juxtaposition and each frame pair supporting complete driving plants overhangingly mounted on opposite sides of said 65 girder.

3. In a semirigid airship, in combination with a gas bag, a metal girder structure extending underneath said bag in close proximity thereof, side cover flaps adapted to 70 envelop said girder, a stiffening front cage mounted on said girder, independent driving plants mounted on either side of said girder, a frame extending from said girder, 75 rudders mounted on this frame, and a horizontal partition member mounted within said girder adapted to serve as platform for crew and passengers.

4. In a semirigid airship, in combination with a gas bag, a metal girder structure extending keel-like below said bag closely adjacent thereto, an umbrella-shaped stiffening cage supported by said girder, comprising curved ribs radially extending from a common center and a plurality of annular 80 members of respectively increasing diameter interconnecting said ribs, and a stiffened bow end for said gas bag, comprising sheaths and ribs therein of substantially the 85 conformation and relative position of said cage ribs, the said two sets of ribs adapted 90 for cooperation to render the bag nose indeformable.

In testimony whereof I have hereunto set my hand in presence of two subscribing witnesses, at Rome, in the Kingdom of Italy, 95 this 2nd day of December, 1920.

CELESTINO USUELLI.
